UNITED STATES PATENT OFFICE.

HARRISON GARNETT, OF NORRISTOWN, PENNSYLVANIA.

COMBINED BEAMING FRAME AND PRESS FOR LOOMS.

Application filed September 14, 1921. Serial No. 500,518.

To all whom it may concern:

Be it known that I, HARRISON GARNETT, a citizen of the United States, residing at Norristown, in the county of Montgomery and State of Pennsylvania, have invented a new and useful Combined Beaming Frame and Press for Looms, of which the following is a specification.

My invention relates to beaming frames or machines used for winding the warp for a loom from a reel onto a beam; and the objects of my improvements are first, to wind the warp from a reel onto a loom-beam evenly and uniformly, through frictional contact with a drum, the beam lying on top of the drum and the latter is driven at one end by suitable gearing, fast and loose pulleys and shafting; second to provide a press or sufficient friction between beam and drum to properly wind the warp onto the beam, (some yarns require more and others less pressing or friction); third to afford facilities for mounting and demounting easily the heavy empty or filled beam from the beaming frame; and fourth to provide means, by which the operator may start and stop the winding of the warp, from any point in the length of the beam. I attain these objects with the beaming frame illustrated in the accompanying drawings, in which:

Fig. 1, is a top view of the beaming frame.

Fig. 2, is a longitudinal elevation of the beaming frame.

Fig. 3, is a cross-section on the line 3—3 of Fig. 2.

Fig. 4, is an end elevation of the beaming frame showing the driving gear for the drum.

Fig. 5, is the other end elevation showing measuring and marking devices.

Fig. 6, is a sectional view on line 6—6 of Fig. 5, and

Fig. 7, is a sectional view on line 7—7 of Fig. 5.

In the drawings D represents the drum made of wood and having a shaft d, which is fast to the drum and journaled in the standards a, a¹. A gear wheel d¹ is fixed to the drum shaft d and meshes with a pinion d² fixed on the counter shaft c, which is journaled in the standards c¹ and f¹. The counter shaft c is provided with a fast pulley c² and a loose pulley c³; and a belt shifter c⁴ is fastened to a rod c⁵, which extends the whole length of the beaming frame to enable the operator to start and stop the rotary

motion of the drum D from any point in the length of the beam. This rod c⁵ is held in position by lugs on the standards f and f¹.

Mounted at the top of the drum D and being in frictional contact with the same, is the beam B to receive the warp from a reel not shown. This beam is of usual construction having a shaft b, a collar b¹ and a brake wheel b² at each end.

This beam B or rather its shaft b is held in a slotted bearing b³ in the standards a and a¹ so that as the beam receives the warp and becomes larger in diameter the shaft b may freely move upward. To press the warp and give proper tension in winding, two levers b⁴, hinged at one end to the standards f and f¹ are provided. These levers b⁴ at about one third of their length bear upon the beam shaft b, and sectional weights b⁵ may be applied to the free end of each lever b⁴ to effect the pressing of the yarn onto the beam B while winding.

To insert an empty beam B into the beaming frame, or remove a beam onto which the warp has been wound, the following mechanism have been provided. The slotted bearings b³ in the standards a and a¹ (Figs. 2, 4 and 6) are formed by having one side b⁶ of each bearing hinged at b⁷, the upper end of b⁶ is normally held in position by a plate b⁸ and pin b⁹; the plates b⁸ are hinged at one end on stud bolts and are slotted on the other end to engage the pins b⁹. e is a shaft journaled in the standards f and f¹, and e¹ is a gear wheel fastened to the same. e² is a pinion meshing with the wheel e¹ and imparts rotary motion to the same when operated by the handle e³. The pinion e² and handle e³ are fastened to a stud shaft e⁴, which is loosely journaled in a cross piece e⁵ of the standards a and f. By partially withdrawing the stud shaft e⁴ from its bearing, the pinion e² may be disengaged from the gear wheel e¹ and the shaft e may rotate freely in either direction for a purpose to be described. At each end of the shaft e is a pin or hook e⁶, to which one end of a chain e⁷ is removably attached, the other end of each chain e⁷ is fastened to a collar b¹⁰ loosely mounted on the beam shaft b.

In operating to insert an empty beam B into the beaming frame, the beam is brought by a truck alongside the drum D and the flanges b¹ overlap the ends of the drum, the chain collars b¹⁰ are slipped over the ends of the beam shaft b; the sides b⁶ of the slot

journals b^3 are lowered as shown in Fig. 4 and the other ends of the chains e^7 are hooked over the pins e^8 ; by now bringing the pinion e^2 into mesh with the gear wheel e^1 , and turning the handle e^3 , the shaft e rotates and winds the chains e^7 onto the shaft e and thereby brings the empty beam into position on top of the drum D and the shaft b into the slot journals b^3 , the hinged sides b^6 thereof are then brought into normal or vertical position and locked therein by the plates b^8 and pins b^9 . The chains e^7 are then unhooked from the shaft e and the pinion e^2 is disengaged from the gear wheel e^1 , so that the shaft e can rotate freely in any direction.

After the beam B has received its quota of warp and it is desired to remove the filled beam from the beaming frame, the operation just described is reversed and the beam is delivered onto a truck or the floor as may be required.

The operation of winding the warp from a reel onto the beam B is as follows:—After the empty beam B is placed in position on the drum D , the ends of the warp are fastened in the usual manner to the beam surface, the weights b^5 are placed on the levers b^4 and power is applied to the shaft c by shifting the belt c^6 from the loose pulley c^3 onto the fast pulley c^2 and by the intervention of the gears d^1 and d^2 , the drum D is rotated, and with the same, in opposite direction, the beam B . The warp coming from a reel is led over the freely rotatable auxiliary shaft e , (Fig. 3) and displays the warp freely to the operator, who, should he discover any defects in the warp, may stop the winding operation at once, from any point in the length of the beam, by shifting the rod c^5 so that the belt c^6 engages the loose pulley c^3 and stop the winding; the defects may then be quickly removed and the winding continued by shifting the rod c^5 in the opposite direction.

It is very desirable in the art of weaving to know the length of the warp on the beam, or to produce marks on the warp to indicate certain length, say forty, sixty or any predetermined number of yards, and for this reason a measuring and marking device may be provided. This measuring and marking device forms the subject matter of a separate application for a patent, and will here be briefly outlined.

The drum is preferably made to measure two yards at its periphery, and therefore as it makes one revolution, two yards of yarn have passed from the reel onto the beam B . The shaft d (Figs. 5 and 6) is provided with a cross head m , in which one or two adjustable pins m^1 are secured, to oscillate the lever m^2 , hinged at m^3 and held back by the spring m^4 . At the upper end of the lever m^2 is adjustably secured a pawl m^5 , which engages

a ratchet wheel m^6 having a certain number of teeth. A pin m^7 in the side of the wheel m^6 is provided to trip a lever m^8 once at every revolution, and this lever fulcrumed in a slotted connection at m^9 has a chalk cup m^{10} , which may be raised or lowered by the two nuts m^{11} . Whenever the lever m^8 is tripped, the chalk cup is thrown up against the passing warp and leaves a mark on said warp.

It will be understood by those skilled in the art that modifications may be made in the arrangement and use of other mechanism without departing from the spirit of the invention, and having thus fully described the nature and objects of my invention, what I claim as new and desire to secure by Letters Patent is—

1. A beaming frame having a drum of a certain diameter, standards in which the drum is journaled, gear wheels, loose and fast pulleys with belt for driving the drum, a belt shifter adapted to control the movement of the drum and be operated from any point lengthwise of the drum, a beam to receive the yarn, slotted journals at each end for the beam, said slotted journals consisting of one stationary and one hinged side, the latter adapted to have its free end locked in place when the beam is in position on and in contact with said drum, or to have the hinged sides occupy a position in which the beam journals may be freed and guided, when the beam is to be mounted or demounted from the frame, substantially as and for the purposes set forth.

2. A beaming frame comprising a frame, a drum journaled therein, means for starting and stopping the rotation of said drum from any point lengthwise of the same, a demountable beam with shaft, slotted bearings on said frame for the beam shaft, the slotted bearings having one side stationary and the other hinged, the latter adapted to hold the beam shaft normally in place, or to form a guide for said beam, when mounting or demounting the beam onto or from the said drum, a lever hinged to each end of said frame and bearing on top of said shaft, sectional weights mounted on rods suspended from the free end of the levers to press the said beam and its contents onto the surface of said drum, substantially as and for the purposes set forth.

3. A beaming frame comprising two standards, a drum journaled therein, means for rotating said drum, a demountable beam with shaft journaled in slots in the same standards, hinged sides forming said slots and means to hold the hinged sides in position, an auxiliary shaft suitably journaled parallel with the beam shaft, a collar loosely mounted on each end of the beam shaft, a chain attached to each collar, means on said auxiliary shaft to fasten temporarily the

other end of said chains to said auxiliary shaft and means to rotate said auxiliary shaft to mount or demount the beam from the top of the drum, substantially as and for 5 the purposes set forth.

4. A beaming frame comprising a frame, a drum journalled therein, means for starting and stopping the rotation of said drum from any point lengthwise of the same, a 10 demountable beam with shaft, slotted bearings on said frame for the beam shaft, the slotted bearings having one side stationary and the other hinged, the latter adapted to hold the beam shaft normally in place, or to 15 form a guide for said beam, when mounting or demounting the beam onto or from the said drum, substantially as and for purposes set forth.

5. A beaming frame comprising a frame, 20 a drum journalled therein, means for starting and stopping the rotation of said drum

from any point alongside of the beam, a demountable beam with shaft, the slotted bearings arranged to have one side hinged and serve as a guide for the beam shaft when 25 mounting or demounting the same, an auxiliary shaft journalled in said frame, a pin or hook at each end of said auxiliary shaft, a chain for each of said pins, a collar on each chain adapted to encircle the ends of the 30 beam shaft, means to rotate said auxiliary shaft to mount or demount the beam onto or from the said drum, substantially as and for the purposes set forth.

In witness whereof I have hereunto set 35 my hand in the presence of two subscribing witnesses.
